Primary Examiner — Leah Macchiarolo*Assistant Examiner* — Taylor O Mortorff(74) *Attorney, Agent, or Firm* — John Yun(57) **CLAIM**

The ornamental design for a roll cage pressure washer as shown and described.

DESCRIPTION

FIG. 1 is a perspective view of our new design.

FIG. 2 is a top view thereof.

FIG. 3 is a bottom view thereof.

FIG. 4 is a right view thereof.

FIG. 5 is left side view thereof.

FIG. 6 is a front view thereof; and,

FIG. 7 is a rear view thereof.

The broken lines shown are for the purposes of illustrating the environment of the article only and form no part of the claimed design.
